H. Ritchie,

Padlock.

No 9,963.

Patented Aug. 23, 1853.

Fig 1.

UNITED STATES PATENT OFFICE.

HENRY RITCHIE, OF NEWARK, NEW JERSEY, ASSIGNOR TO HENRY RITCHIE, SAMUEL C. THOMPSON, AND G. W. WESTERFIELD.

PADLOCK.

Specification of Letters Patent No. 9,963, dated August 23, 1853.

To all whom it may concern:

Be it known that I, HENRY RITCHIE, of Newark, in the county of Essex and State of New Jersey, have invented a new and 5 useful Improvement in Spring-Padlocks; and I do hereby declare that the following is a full, clear, and exact description of the same, reference being had to the annexed drawings, making a part of this 10 specification, in which—

Figure 1, is a view of my improved padlock, in a locked state; the front plate of the case being removed in order to show the interior. Fig. 2, is the same view as 15 Fig. 1; the padlock being unlocked.

Similar letters of reference indicate corresponding parts, in each of the two figures.

This invention relates to a new and useful improvement in spring padlocks, and 20 consists in the combination of a bolt, toothed tumbler, and guard, so arranged as to prevent the bolt from being forced from the shackle in the bow, by means of blows, or by violently striking the case of the lock; 25 the toothed tumbler also allowing the lower end of the bow, when pressed in the lock, to operate the guard, and thus allow the bolt or its projection to pass into the shackle.

To enable others skilled in the art to fully 30 understand and construct my invention, I will proceed to describe it.

A, represents the case of the lock, which case is of the usual form; and, B, is the bow, attached to the case, A, in the usual 35 manner; (a), being the pivot of the bow.

C, is the bolt within the case. This bolt is of irregular form, as shown in both figures; and it works upon a pivot, (b). The upper spur or projection, (c), is the portion 40 of the bolt which passes through the shackle, (d), of the bow, B. The position of the shackle is shown by dotted lines. The spring of the bolt, C, is represented by, (e).

D, is a tumbler, working on a pivot, (f); 45 see dotted lines. This tumbler is underneath or behind the bolt, C. The spring of the tumbler is represented by, (g). On the upper part of the tumbler there is a small rounded prominence or tooth, (n), which 50 passes into the shackle (d) and rests or bears against the edge of the spur or projection, (c), when said spur or projection is in the shackle; as seen in Fig. 1. On the right side of the tumbler, there is a projection, (h), which rests or bears upon a

ledge (i), when the parts are in the position shown in Fig. 1. The spring, (g), keeps the tumbler in this position. On the projection, (h), there is a tooth, (j), which bears against the right side of the bolt, C, 60 and underneath a notch in the bolt, when the parts are in the position shown in Fig. 1.

E, is a guard or lever, having its fulcrum at, (k). This guard is kept firmly upon the upper part of the bolt, by a spring, (l); 65 and the outer edge of the guard is opposite a shoulder, (m), in the upper part of the bolt, that is, when the parts are in the position shown in Fig. 1, and the padlock is in a locked state.

By referring to Fig. 1, it will be readily seen that, when the padlock is in a locked state, it is impossible to force back the bolt or drive the spur or projection, (c), from without the shackle, (d); because the tooth, (j), bears against the right side of the bolt, C, and underneath the notch, and the guard, E, against the shoulder, (m). In order to withdraw the bolt from the shackle, the guard, E, and tooth, j, must first be elevated 70 or raised so as to clear the bolt. This is done by means of the key, which first acts upon the tumbler, D, and raises the stop, (j); the tumbler also raising the guard, E. The key then acts upon the bolt; and the spur or projection, (c), is withdrawn from the shackle, (d). When the key is turned entirely around, the parts return to their original 75 position; and in order to lock the bow, B, it is merely pressed downward; the lower end 80 of the bow forcing back the prominence, (n), and causing the tumbler to free the guards from the bolt, until the shackle, (d), comes opposite the spur or projection, (c), when 85 said spur is forced into the shackle, by the spring, (e), of the bolt.

I am aware that several devices have been employed for preventing the bolt from being forced backward by striking the case of the lock. H. C. Jones has one patent in which 90 he employs two bolts; one termed a "slide" bolt, and the other a "turning" bolt; both of these bolts work or pass into the shackle; and the idea is, that if one bolt be forced out of the shackle by blows, the other bolt 100 will remain in the shackle. There is no doubt but what this plan is an improvement over the single bolt originally used; but two bolts may be forced from the shackle by repeated blows; as H. C. Jones employs no 105 110

guard or stop; neither has he a tumbler and both bolts are also liable to derangement by striking the case. In my improvement, I employ only one bolt; and I prevent that 5 bolt from being deranged or forced back by blows, by means of the tumbler and guard.

Having thus described my invention, what I claim as new, and desire to secure by Letters Patent, is—

10 The combination of the bolt, C, guard, E,

and the double toothed tumbler, D; one tooth, (n), of said tumbler, fitting in the shackle, (d), and the other tooth, (j), fitting in the notch at the back of the bolt. The bolt, guard, and tumbler operating as set 15 forth in the body of the specification.

HENRY RITCHIE.
